UNITED STATES PATENT OFFICE.

GEORGE A. DENNIS, OF OAKLAND, CALIFORNIA, ASSIGNOR OF FORTY-NINE ONE-HUNDREDTHS TO MALOTT & PETERSON, OF SAN FRANCISCO, CALIFORNIA, A CORPORATION.

COMBINATION FLOOR POLISHING AND SANDPAPERING TOOL

1,175,245.

Specification of Letters Patent. Patented Mar. 14, 1916.

Application filed April 17, 1915. Serial No. 22,214.

To all whom it may concern:

Be it known that I, GEORGE A. DENNIS, a citizen of the United States, residing at Oakland, in the county of Alameda, State 5 of California, have invented a new and useful Combination Floor Polishing and Sandpapering Tool, of which the following is a specification.

My invention relates to improvements in 10 a floor polishing and surfacing tool, which can be easily and quickly converted into a sand-papering or polishing tool, the construction being such that the sand-paper or polishing cloth can be instantly removed 15 or replaced, also the clamping arrangement admits of a minimum amount of waste of material. I attain these objects by the construction illustrated in the accompanying drawing, in which the figure is a perspective view of the tool in the position ready 20 for use, half of the drawing showing the arrangement when used as a sand-papering or polishing device, the other half showing the tool with sand-paper or polishing cloth 25 removed, which is the case when used as a surfacing tool.

The frame A is a metal casting, having the ends formed in the manner as shown at B—B, and fluted on the bottom surface as 30 shown in the drawing.

C is a spring retainer, the ends of which fit into the grooves forming the channel in back of B. B.

D is a bracket riveted firmly on the top 35 and in the center of the spring retainer C, as shown in the accompanying drawing. The two holes E—E in the turned up portions of D, are used for fastening a suitable handle, in a manner to allow freedom of 40 movement of the tool.

F is a lever, pivoted to the drop bracket G, which in turn is fastened rigidly to the underside of C, substantially as shown.

H—H are two pieces of wire each fastened on their outer ends in an eyelet rivet 45 I—I. These rivets I—I are securely fas-

tened into the center of the ends of C. The inner ends of H—H are fastened in the two ears of the lever F in the manner and as shown in the drawing. The mounting of 50 the lever F, in relation to two pieces of wire H—H, is such, that moving the lever backward or forward will draw in the ends of the spring C, or release same, according to 55 which way the lever is moved.

J is a piece of backing preferably a piece of carpet cut to fit over the under portion of A and sufficiently long to permit bending over the ends of B—B.

K is a piece of sand-paper cut to match 60 backing J.

To assemble the tool first place the carpet or backing in position over frame A, then stretch the sand-paper over the backing, place the spring retainer C in place and 65 release lever F. The tool is now assembled, ready to be used for sand-papering purposes. When the tool is to be used for polishing, remove the sand-paper, but retain the carpet or polishing cloth on the frame 70 A. When the tool is to be used for rough surfacing or scraping, remove the remaining carpet or polishing cloth.

Having thus described my invention, what I claim as new, and desire to secure by Letters Patent, is:

In a device of the character described, a frame provided with upturned ends, a spring retainer to engage said upturned ends, a bracket secured to the under side of 80 said retainer, a lever pivoted to said bracket and links connected to said lever and to the outer ends of the spring retainer to expand and contract said retainer.

In testimony whereof, I have signed my 85 name to this specification in the presence of two subscribing witnesses.

GEORGE A. DENNIS.
